(57) CLAIM

The ornamental design for a container for a personal care product, as shown and described.

DESCRIPTION

FIG. 1 is a perspective view of a container for a personal care product showing our new design; FIG. 2 is a front elevational view thereof;

FIG. 3 is a side elevational view thereof, the opposite side elevational view being a mirror image thereof;

FIG. 4 is a top plan view thereof; and,

FIG. 5 is a bottom plan view thereof.

The broken lines showing the bottom and central region of the container are for illustrative purposes only and form no part of the claimed design.
